[57] CLAIM

The ornamental design for a flower pot cover, as shown.

DESCRIPTION

FIG. 1 is a perspective view taken from the top and front side of a flower pot cover showing my new design;

FIG. 2 is a top plan view thereof;

FIG. 3 is a front elevational view thereof, the right elevational view, the left elevational view and the rear elevational view being identical to that of FIG. 3; and FIG. 4 is a bottom plan view thereof.

FIG. 1

FIG. 4
